(57) **CLAIM**

The ornamental design for a container with ultrafine bubble generation part, as shown and described.

DESCRIPTION

FIG. 1 is a front view of the container with ultrafine bubble generation part, the rear being a mirror image of the front; FIG. 2 is a left side view thereof, the right side being a mirror image of the left side;

FIG. 3 is a top view thereof;

FIG. 4 is a bottom view thereof;

FIG. 5 is a top perspective view thereof;

FIG. 6 is a bottom perspective view thereof;

FIG. 7 is a front view thereof in a disassembled state;

FIG. 8 is a top perspective view thereof in a disassembled state;

FIG. 9 is a top view of the ultrafine bubble generation part;

FIG. 10 is a bottom view of the ultrafine bubble generation part;

FIG. 11 is a top perspective view of the ultrafine bubble generation part; and,

FIG. 12 is a bottom perspective view of the ultrafine bubble generation part.

The broken lines of FIGS. 1-8 illustrate portions of the container with ultrafine bubble generation part that form no part of the claimed design.

1 Claim, 9 Drawing Sheets
